SOUND TRANSMISSION CIRCUITS

Lindsay M. Applegate, Portland, Oreg., assignor
to John B. Brady, Somerset, Md.

Application March 2, 1927. Serial No. 172,084

3 Claims. (Cl. 179—171)

This invention relates generally to the transmission of sound, and specifically to the transmission of energy of sound frequencies in signal transmission systems. The purpose of this invention is to extend the range of sound or audio frequencies that can be accommodated by modulated transmitters for transmitting signals, such as musical programs requiring an extensive range of sound frequencies. Such programs require, for reasonably good reproduction, sound frequencies from about 50 to about 8,000 cycles per second. For perfect reproduction a transmitter should be able to accommodate the entire audible range of sound frequencies which, in the case of the most sensitive human ear, is considered to be a range of about 4 to 32,000 cycles per second.

The actual limitations of individual instrumentalities for transmitting a broad range of sound frequencies are well known in the art. This is true particularly of sound transmission lines and transformers. Examples of such limitations are found frequently in audio transformers which will not usually operate with uniform effect over a range more extensive than from about 100 cycles per second to about 3,000 cycles per second, or, expressed as a ratio, of one to thirty. Such a transformer will usually operate with gradually decreasing effect both at the lower and upper ends of its frequency range beyond the frequencies stated. It appears to be practically impossible to construct single sound transmission circuits that will accommodate with complete uniformity a range of frequencies as great as that desired for reproduction of signals of the character of musical programs.

The limitation of about one to thirty mentioned above remains approximately the same regardless of the position of the range in the frequency scale. That is, a transformer can be designed with a range of from 4 to 120 cycles per second, or from 1,000 to 30,000, for example, but the ratio of the lowest to the highest frequency is more or less constant.

In view of the fact that single sound circuits cannot accommodate all the frequencies to be desired in a signal, a plurality of circuits, each accommodating a particular range of frequencies, can be combined to accommodate the entire range desired. For example, if a transformer for all the frequencies from 4 to 32,000 cycles per second were desired, three transformers, one having a range of from 4 to 80 cycles per second, one having a range of from 80 to 1,600 and one having a range of from 1,600 to 32,000 cycles per second, properly combined, would accom-

modate the entire range of frequencies of from 4 to 32,000 cycles per second.

In my invention this principle is made use of in accomplishing the modulation of radio frequency oscillations over a broad range of sound frequencies.

In the accompanying drawing, I illustrate my invention diagrammatically in simple form. In the drawing the letters A, B, and C are used to designate three limited, partially overlapping ranges or bands of sound frequencies.

Three circuits, the first including an amplifier 1, and a coil 2, the second an amplifier 3 and two coils 4 and 5, and the third an amplifier 6 and a coil 7, respectively accommodate the three bands of

sound frequencies A, B, and C, which, collectively, provide for a comparatively extensive range of sound frequencies.

Energy of the several frequency bands is delivered to the circuits shown from such appropriate circuits as may be desired. These, since they are known to the art in various forms, are indicated in the drawing by three telephone transmitters 8, 9, and 10, of different sizes, the smallest one, 8, representing the higher frequencies, the middle sized one, 9, the intermediate frequencies, and the largest one, 10, the lower frequencies.

The three telephone transmitters together are intended to accommodate the entire range of sound frequencies required for the reproduction of the signal concerned.

Coils 2 and 4 are parts of a transformer 11 which also includes another coil 12. Coils 5 and 7 are parts of a second transformer 13 which has a third coil 14.

Coils 12 and 14 respectively connect with two modulators 15 and 16 which together modulate the output of an oscillator 17.

The power source and usual connections, being well understood, have been omitted for convenience.

In the operation of the invention shown, the amplifiers 1, 3, and 6 have delivered to them energy of the frequencies characteristic of the circuits preceding them. For example, circuit A

may deliver energy of frequencies between 20 and about 210 cycles per second, circuit B frequencies from 190 to 2,000, and circuit C frequencies from 1,800 to 18,000 cycles per second.

Together they would cover a range of from 20 to 18,000 cycles per second. In the frequency band limits stated, there is a certain overlapping, for example the

A and B ranges overlap in the frequencies from 190 to 210 cycles per second, and the B and C in the frequencies 1,800 to 2,000 cycles per second.

This is necessary if a uniform effect of transmission over the entire range is to be obtained be-

110

105

100

95

cause the lines, transformers, and so forth, associated with the respective frequency bands accomplish uniform transmission only over a limited portion of their respective frequency ranges, and they decrease in effectiveness more or less gradually at their upper and lower limits. In these individual frequency bands the ratio of the upper to the lower frequencies is about 10½ to 1, while that of the total frequency range of the three in combination is 18,000 to 20 or 900 to 1. The amplifiers 1, 3, and 6 deliver their energy to the transformers 11 and 13. Amplifier 1 delivers all its energy to transformer 11 and coil 12 through coil 2. Amplifier 3 delivers part of its energy to transformer 11 through coil 4 and part to transformer 13 through coil 5. Amplifier 6 delivers all its energy to transformer 13 and coil 14 through coil 7. Thus transformer 11 receives all the "A" frequency energy and part of the "B" frequency energy, and transformer 13 receives part of the "B" frequency energy and all of the "C" frequency energy. If the coils in the two transformers 11 and 13 are correctly proportioned, coil 12 will carry frequencies from 20 to somewhat more than 600 cycles per second, and coil 14 frequencies from somewhat less than 600 to 18,000 cycles per second. In both coils the ratio of the upper to the lower frequencies is about 30 to 1. The two coils 12 and 14 control respectively modulators 15 and 16 which, coacting, modulate the output of oscillator 17 through the entire range of frequencies accommodated by the several circuits A, B, and C collectively.

In the above explanation the respective ranges of frequencies of the three amplifier circuits were described by the ratio of 10½ to 1. Under some conditions, the amplifier circuits have such ranges individually that the frequency ranges of the transformers 11 and 13 are the principal limiting factors. Under such conditions the characteristics of the transformers determine the limits of the frequency bands.

It should be understood in connection with the drawing that the selection of three as the number of amplifying circuits and two as the number of modulating circuits has been chosen arbitrarily for purposes of explanation and illustration. Any convenient pluralities of amplifying circuits and modulating circuits can be used at will. It should be understood also that the particular form of connection shown between the modulators and the oscillator need not be employed. Any of the usual modulating connections may be used.

What I claim is:

1. A system of modulation which comprises

an oscillating circuit, a plurality of modulating circuits operatively associated therewith, said modulating circuits being individually operative for limited ranges of modulating frequencies, said limited ranges of modulating frequencies partially overlapping and together accommodating an extensive range of modulating frequencies, a plurality of amplifying circuits operatively associated with said modulating circuits, said amplifying circuits being individually operative for limited ranges of modulating frequencies, said limited ranges together covering an extensive range of modulating frequencies, the number of modulating circuits being different from the number of amplifying circuits. 80 85 90

2. In multifrequency transformers, the combination of a plurality of primary circuits, a plurality of magnetic circuits, and a plurality of secondary circuits, the number of which is different from the number of primary circuits, the whole being arranged so that said primary circuits are adapted respectively to particular ranges of frequencies, and said secondary circuits adapted to other particular ranges of frequencies, the said primary ranges of frequencies together comprising a wide range of frequencies, and the said secondary ranges together comprising the same wide range of frequencies as the primary, one of said secondary circuits receiving substantially all the frequencies of one 100 of said primary circuits, another of said secondary circuits receiving substantially all the frequencies of another of said primary circuits, and both of said secondary circuits receiving part of the frequencies of a third of said primary circuits. 105 110

3. In multifrequency transformers the combination of a first plurality of electric circuits arranged to accommodate, individually, limited ranges of frequencies partially overlapping, and, collectively, accommodating an extensive range 115 of frequencies, a plurality of magnetic circuits less in number than the number of circuits in the said first plurality, and a second plurality of electric circuits arranged to accommodate, individually, limited ranges of frequencies partially 120 overlapping and, collectively, accommodating the same extensive range of frequencies as is accommodated by the said first plurality of electric circuits, the whole being arranged so that energy of the said extensive range of frequencies 125 is transferred between said first plurality and said second plurality of electric circuits, at least one electric circuit of said first plurality of electric circuits dividing its energy between two of said magnetic circuits. 130
